By Francis D. Brown his Atty.

UNITED STATES PATENT OFFICE.

FRANCES S. JEROME, OF SAN FRANCISCO, CALIFORNIA.

TRUNK.

SPECIFICATION forming part of Letters Patent No. 499,835, dated June 20, 1893.

Application filed May 2, 1892. Serial No. 431,436. (No model.)

To all whom it may concern:

Be it known that I, FRANCES SHELDON JEROME, a citizen of the Republic of France, residing at San Francisco, in the county of 5 San Francisco and State of California, have invented certain new and useful Improvements in Trunks for Travelers, of which the following is a specification:

Referring to the accompanying drawings 10 which form part of this specification, Figure 1 is a view in perspective of the trunk closed. Fig. 2 is an elevation of the trunk set on end with the front open. Fig. 3 is a central vertical section of $\alpha\alpha$ Fig. 2. Fig. 4 is a front view 15 of the body with the drawers removed. Fig. 5 is a top view of Fig. 2 with the top-cover closed. Fig. 6 is a general perspective view showing the ward-robe compartment, the writing-desk attachment in position on the 20 front and the dressing-case on the top set up for use. Fig. 7 is a vertical transverse section through the ward-robe compartment, and Fig. 25 7^a is a horizontal transverse section. These two sections are taken through the middle of this compartment in two planes one set at a right angle to the other. Fig. 8 is a view in 30 perspective of the toilet-box and mirror removed from the trunk.

My improved trunk for travelers comprises 35 mainly, two compartments one of which forms a ward-robe and the other a chiffonière and dressing-case. When in use it is made to stand on end.

The compartment A for the ward-robe is of 40 less depth than the portion B containing the drawers and boxes, and these sections when closed produce a compact chest or trunk with all the parts in proper condition for handling in transportation. The two sections A A^x 45 are separable on the line α^x on all sides and form rectangular frames to the adjacent edges of which all around a plaited or folded canvas C C is attached as shown in Figs. 6, 7, 7^a in proper manner to produce flexible extensible walls capable of being drawn out as 50 shown in Fig. 6. Swinging brackets or arms b b b with hooks upon which to hang articles of apparel are pivoted to pins b' of graduated lengths, and the latter are connected to the top board of the ward-robe compartment so that the arms b may be folded inward and back-

ward without coming in contact each with the other as shown in Fig. 7^a when the canvas portion is collapsed and shut in between the two frames. In that position the canvas web 55 should fold inward so that a close joint will be formed between the meeting edges of the two frames; and, by means of hooks, catches, bolts or other like means Q operating upon the inside, the two parts are locked together. 60 The hinged cover D on the outer frame shuts down upon the ward-robe and forms the door of that compartment. The front side of the other compartment B is attached by hinges d d to form the door or cover E over the 65 drawers and boxes. When the trunk is set on end this door will assume the position shown in Fig. 2 to expose to view a series of drawers and boxes F, F, F^x F² of different capacities. These drawers are constructed of 70 some light strong material such as papier maché and are placed on top of each other cross-wise in the compartment and fill the entire space therein, save and except the space marked G which in this present arrangement 75 is divided from the front by an upright partition g^x to form a hat-box. A removable sliding cover G² divides this box into two separate spaces whenever two smaller compartments are required instead of the single deep 80 box G.

The space in front of the partition g^x contains the toilet-box F⁴ and both spaces are closed in on the top by the hinged cover H.

The toilet-box has trays I forming pockets 85 or receptacles for various articles of the toilet, and on the top is fitted a hinged folding mirror K as shown in Fig. 8.

The table L is suspended by the chains f f or by braces beneath it in front of the drawers just below the desk compartment F³ which 90 consists of two horizontally swinging doors covering a space for containing writing material.

Access to the ward-robe compartment is had 95 through the door D, and to the dressing or toilet-case by raising the cover H.

All the parts can be easily and quickly adjusted for use or folded up for traveling, the different sections and covers or lids being 100 provided with suitable catches and locks such for instance as shown at Q'.

Having thus described my invention, what I claim, and desire to secure by Letters Patent, is—

1. The herein described trunk for travelers consisting of two main portions separated by a rigid partition, one portion comprising two frames A and A^x connected by accordion-folded canvas C, and a folding door D in the outer frame, and the other portion B having a series of drawers and the like with a door E for covering them, as and for the purpose set forth.
2. The herein described trunk for travelers consisting of two main portions separated by a partition, one portion comprising two frames A and A^x connected by accordion-folded canvas C of a size to fold within the frames when their edges come together, a lock for detachably securing said edges together, and a folding door D in the outer frame, and the other portion B having a series of drawers and the like, and means for securing them in closed position, as and for the purpose set forth.
3. The herein described trunk for travelers adapted when open to stand on end and consisting of two main portions, one portion comprising two frames A and A^x connected by accordion-folded canvas, pins of graduated length in the top board of this portion, arms pivoted to said pins and having clothes hooks, and a folding door D in the outer frame, and the other portion B having a series of drawers and the like, and means for securing them

in closed position, as and for the purpose set 35 forth.

4. The herein described trunk for travelers consisting of two main portions A and B, the former being arranged so that clothes may be hung therein, and the latter having a series 40 of sliding drawers, two small doors F³ covering a space for writing materials, a table L hinged just below said space, chains f connecting the outer corners of the table with the body B above, and a hinged door E 45 adapted when closed to retain said drawers in place and to hold the table folded and the small doors closed, as and for the purpose set forth.

5. The herein described trunk for travelers, 50 the same consisting of two main portions A and B, the former being arranged so that clothes may be hung therein, a series of drawers in the latter portion adapted to move horizontally when the trunk is set on end, a hat 55 box G and toilet box F⁴ fast in the then upper end of the portion B, partitions and trays in these boxes, and a hinged cover at the upper end of this portion for permitting access to these boxes, as and for the purpose set 60 forth.

In testimony that I claim the foregoing I have hereunto set my hand and seal.
